UNITED STATES PATENT OFFICE.

ERNEST RICHARDSON, OF COLLEGE HILL BOROUGH, PENNSYLVANIA.

BILLBOARD.

Application filed October 5, 1923. Serial No. 666,788.

To all whom it may concern:

Be it known that I, ERNEST RICHARDSON, a citizen of the United States, residing at College Hill Borough, in the county of Beaver and State of Pennsylvania, have invented new and useful Improvements in Billboards, of which the following is a specification.

My invention relates to improvements in bill-boards or signs employed for advertising. It is the principal object of the present invention to provide a novel molding or border for bill-boards. The said molding is made up of metal, preferably porcelain enameled, composed of several sections adaptable to bill-boards of different or irregular dimensions. My molding is adapted for use with bill-boards of any size whether composed of a single panel or a number of panels arranged end to end.

Referring to the accompanying drawings, Fig. 1 is a front elevation of a bill-board, broken off at one end, showing my improved molding applied thereto; Fig. 2, a section 25 on the line II—II of Fig. 1; Fig. 3, a section on the line III—III of Fig. 1; Fig. 4, a section on the line IV—IV of Fig. 1; Fig. 5, a section on the line V—V of Fig. 1; Fig. 6, a side elevation of a corner piece forming 30 a part of my invention; and Fig. 7, an elevation of the frame or foundation to which my molding may be attached, a corner being broken away.

On the drawings, 1 and 2 designate the side 35 members of the frame for a single panel, 3 is the bottom member thereof, 4 the top member which is somewhat wider than the other members, and 5 the back member. The said members may all be of wood arranged 40 so that the members 1, 2, 3, and 4 form an elevated rib or border standing out from the back member 5. The frame is therefore a pan-shaped support for my molding and such advertising as may be applied to the 45 member 5. A number of panels may be arranged end to end, as shown in Figs. 1 and 2, where the second or right-hand panel is shown constructed like the first or left-hand panel. I have shown the member 1 of the 50 first panel abutting the member 2 of the second panel, but the last named members 1 and 2 may be a single member having the thickness of both the members 1 and 2 combined. The back members 5 of the panels 55 may be made continuous throughout the length of the bill-board and the intermedi-

ate abutting members 1 and 2, or a member having their combined thickness, may lie directly on the back member 5.

At each corner of a panel is applied a corner member 6 of my molding. The corner members are interchangeable. Each has two arms or members 7 and 8 arranged at right angles to each other, so as to fit the angles or corners of the panel. The corner members are made of thin metal having their outer portions lying on the front faces of the members 1, 2, 3, and 4, while their inner edges lie upon the back member 5. The members 6 are preferably fluted or grooved, 60 as shown, across the angles between the back member 5 and the adjacent remaining frame members 1, 2, 3 and 4. The members have suitable slots 7' near their inner edges and also in those portions which are to lie on 75 the front faces of the members 1, 2, 3 and 4.

8' are the side members or strips of molding which span the spaces between consecutive corner members 6. They are constructed like the corner members except that they 80 are straight. Their cross-sectional shape is the same as that of the corner members. Their ends lie upon the slotted ends of the members 6 and are provided with screws 9 which extend through the members 8' and 85 6 and into the frame members. The slots 7' provide means for compensating for irregularities in the lengths of the sides and ends of the panels.

The molding covers only the lower portion 90 of the front of the member 4. The cap member 10 is an L-shaped on angular strip of sheet-metal having one member 11 lying on the top of the member 4 and the other member 12 covering the upper portion of 95 the front face of the member 4, and also covering the upper portion of the adjacent corner members 6 and the intervening member 8'. The cap is held in place by screws 13 extending through it and into the member 4. Where there are a plurality of panels, 100 as in Figs. 1 and 2, the cap may extend as a single piece over the top of more than one panel.

It is evident that the corner members 6 105 may lie upon the side members 8' instead of under the same.

I claim—

1. In a rectangular or similar bill-board, a frame having a raised border and a back 110 member, in combination with a sheet-metal molding comprising side members and el-

bow-shaped corner members, the ends of the side and the corner members overlapping, and fastening devices extending through both members and into the frame, one of the 5 molding members having at each overlapping place a slot to receive a fastening device to compensate for irregularities in the lengths of the sides of the frame.

2. In a rectangular or similar bill-board, 10 a frame having a raised border and a back member, in combination with a sheet-metal molding comprising side members and elbow-shaped corner members, the ends of the

side and the corner members overlapping, fastening devices extending through both members and into the frame, one of the molding members having at each overlapping place a 15 slot to receive a fastening device to compensate for irregularities in the lengths of the sides of the frame, and a cap L-shaped in 20 cross-section covering the top of the frame and overlapping the upper edge of the top edges of the molding.

In testimony whereof I hereunto affix my signature this 3rd day of October, 1923.

ERNEST RICHARDSON.
